(57) CLAIM

The ornamental design for a corner dresser, as shown and described.

DESCRIPTION

FIG. 1 is a perspective view of a corner dresser showing my new design;

FIG. 2 is a left side elevational view thereof;

FIG. 3 is a right side elevational view thereof;

FIG. 4 is a top plan view; and,

FIG. 5 is a bottom plan view thereof.

The broken lines shown in FIG. 5 are for illustrative purposes only and form no part of the claimed design.
